UNITED STATES PATENT OFFICE.

GEORGE WINTER HERBEIN, OF SEATTLE, WASHINGTON.

BRIQUETING-MACHINE.

965,298.

Specification of Letters Patent. Patented July 26, 1910.

Application filed February 12, 1908. Serial No. 415,535.

To all whom it may concern:

Be it known that I, GEORGE WINTER HERBEIN, a citizen of the United States, residing at Seattle, in the county of King and State of Washington, have invented certain new and useful Improvements in Briquetting Machines, of which the following is a specification, reference being had therein to the accompanying drawings.

10 The object of this invention is the provision of an efficient and economically operated machine for compacting artificial fuel or analogous substances into briquets.

With this general object in view the invention consists in utilizing a reciprocating plunger in conjunction with a plurality of dividing plates which operate in a barrel wherein the compacting of the briquets is accomplished.

20 The invention further consists in the appliances to supply the material for treatment and the aforesaid dividing plates to the machine, and as they are emitted therefrom to segregate such plates from the finished product and successively return the same for a repetition of the operations.

The invention still further consists in the novel construction, adaptation and combination of the various parts of the apparatus, 30 as will be hereinafter described and claimed.

In the drawings, where similar reference characters designate corresponding parts in all of the views, Figure 1 is a longitudinal view partly in vertical section and partly in side elevation of the head-end of a machine embodying my invention; Fig. 2 is a vertical sectional view of an intermediate portion and foot end of the device; Fig. 3 is a plan view of that part of the machine 35 which is illustrated in Fig. 1; Fig. 4 is a plan view of the other end which is included in Fig. 2; and Fig. 5 is a cross sectional view taken through 5—5 of Fig. 4 drawn to an enlarged scale.

45 According to this invention, I employ a barrel with its axis arranged horizontally, or nearly so, and is desirably comprised of a number of sections, 10, 11, 12, and 13, which are rigidly connected by suitable means, such 50 as screw-bolts 14 for uniting the flanges 14' provided upon the adjoining ends. The sections 10, 11 and 13 are all bored to substantially the same diameters, but section 12 is bored to a greater diameter. The section 10 55 which is adjacent to the head end of the

machine is made somewhat stronger than the others so as to withstand the greater stresses to which it is subjected and is further strengthened by a surrounding sleeve 15. The other sections are inclosed by tubes 60 16 to afford annular spaces 17 for a heating-medium, such as steam, which is supplied, from a conduit 18, see Fig. 3, leading from a source of supply, to the cavity 17' formed in said sleeve at the head end of the barrel, 65 and thence passes through a communicating duct 19 into the adjacent space 17 and so on through communicating ducts 19' and spaces to a discharge pipe 20.

The barrel-section 10 is provided with an 70 opening to receive the material to be operated upon from a hopper 21 and to the front of such opening and to the top of the barrel-bore is a recess 22 to house the bent end 23 of a vertically slidable gate 23' which 75 is yieldingly pressed downwardly by a spring 24 to close the bore of the barrel when the plunger 25 is retracted, as will be more fully explained hereinafter. The plunger 25 is fitted to the barrel-bore and has one end 80 supported thereby while its forward end may be carried by a cross-head 26 mounted in slide-ways 27 which are rigid upon a base frame 28 fixedly connected to the barrel. Reciprocating motion is imparted to the 85 plunger from any suitable power means as, for example, fluid pressure operating in a steam or hydraulic cylinder, or it may be actuated by the illustrated devices, comprising a rotary cam 29 wherewith rollers 30 90 and 31 carried by said cross-head 26 are in engagement with the outer and inner peripheral surfaces 29' and 29'', respectively, of the cam flange 29'''. The cam is mounted upon a power driven shaft 32 which is journaled in bearing-boxes 33 formed in or rigidly secured to said frame. Set collars 34, 34' are carried upon the plunger 25 in adjusted positions and between these collars is a loose sleeve 35 of less length than the 100 distance said collars are spaced apart. Sleeve 35 has laterally extending pins 35' whereupon are rollers 36 which are adapted for engagement with the branches 37 of a bifurcated lever-arm 37' which is fulcrumed 105 to a pivot 38 and is provided in its other arm 37'' with a slot 37''' wherethrough extends a pin 39 of a block 40. This block is vertically movable in a guide-box 41 disposed directly below an opening 42 in the 110

bottom of the barrel and likewise in vertical alignment with the gate part 23.

Extending lengthwise of the machine is a trough 43 for the conveyance of the divider-plates 51 by an endless chain 44 which passes about wheels 45 and 46 disposed in proximity to the opposite ends of the barrel. Of these wheels 45 may be the driver mounted upon a transverse shaft 47 deriving its rotary motion from any suitable power means as, for example, the cam-shaft 32 through sprocket chain 48 and wheels 49 and 50 mounted upon the respective shafts. At the head end of the trough 43 is a delivery chute 43', see Fig. 3, down which by the action of gravity, roll the dividing plates 51 into the path of travel of the block 40. At the rear end, the barrel has connected thereto a spout 52 having its outer end inclined upwardly as at 52' and at a short distance beyond this spout is a lead-way 53 into which the briquets are discharged.

54 is a spider, see Figs. 4 and 5, which is mounted for rotation on a spindle 55 and has the ends of its arms formed concave, as at 56, and are arranged to revolve in the gap intermediate the spout 52 and the lead-way 53. Upon each of the spider arms is a stud 57 which is successively engaged in the notch 58 of arm 58' of a bell-crank which is pivoted at 59 and has a bolt 60 extending through the other arm 58'' and also through a flange 28' of the base-frame. A spring 61 is provided on the bolt between an adjustable nut 60' and said flange for the purpose of causing the bell-crank to resiliently engage the pins as presented.

The operation of the invention as hereinbefore disclosed may be described as follows: Assuming that the material to be compacted into briquets is supplied to the hopper 21 in ample quantity to meet the demand and that the shaft 32 is rotating the cam 29, the cam then with each rotation and through the office of the rollers 30 and 31 in engagement therewith will project the plunger 25 into the barrel and retract it therefrom to an extent governed by the eccentricity of the cam. In the former of these motions the plunger carries therewith a dividing plate 51, which was in the preceding retractile motion of the plunger, elevated into the barrel-bore, and the dividing-plate conveys in its advance a charge of the material deposited into the barrel-bore to beyond the admission opening from the hopper 21. When the plunger has traveled to its full extent into the barrel, the continued rotation of the cam coacts with the roller 31 to withdraw the plunger releasing the gate 23' so that the spring 24 can assert itself and depress the gate to prevent the material falling into the barrel from following the plunger in its retrograde movement. During the retraction of the plunger, it is drawn

through the sleeve 35, in opposition to the weight of the block 40 acting through the lever arms 37, until the sleeve is impinged by the collar 34 whereupon the sleeve is compelled to accompany the plunger during the remainder of its retractile movement. During the lost motion with respect to the sleeve, that is while the plunger is moving therethrough, the referred to lever is uninfluenced by the latter, but when motion is imparted to the sleeve the lever is affected to raise the block 40 and elevate a dividing plate 51 which was previously received thereupon from the trough outlet 43'. The dividing plate in ascending encounters the bent part 23 of the gate 23' to open the passage-way for the advance of the dividing plate when projected by the plunger in the next operative stroke of the latter. In such operative stroke the plunger is moved sufficiently far to dislodge the dividing plate from on top of the block 40 and also to receive the thrust of the gate before the set collar 34' comes in contact with and actuates the sleeve 35 to allow the controlling lever to lower the block 40 for the reception of another dividing plate. This completes a cycle of operation of the plunger and also of the means for serving the dividing plates. A repetition of such cycles of operation compacts the charges into a series of briquets 62 interposed between the successively served dividing plates and by being compressed as they are forced toward the delivery end of the barrel they are thereby compacted into formed condition under the action of heat received from the steam about the barrel.

When the briquets have arrived at the section 12, that with the enlarged bore, they expand diametrically and in the endeavor to resume the smaller diameters necessary to enter the smaller bore of the adjoining section 13 resist the progressive movement of the following briquets and thus furnish retarding force to react against the compressing power delivered by the plunger.

The briquets as they are ejected from the barrel adhere, according to the binding ingredient employed, more or less to the contacting dividing plates and to overcome which a bend is provided in the spout 52 for deflecting the line of briquets and dividing plates so as to disconnect one from another. When a briquet arrives at the extreme end of this spout it passes through the concave portion of an arm of the spider 54 and into the chute 53, whence it rolls into a storage bin or other receptacle therefor. The dividing plates 51, however, being of greater weight than the briquets press downwardly upon an arm with sufficient force to overcome the power of the spring 61 so that the bell-crank is caused to yield to release the then engaged stud and allow the spider to be rotated until the next stud is caught in

the notch 58 of the bell-crank. In such movement of the spider the affecting dividing plate which is deposited in the trough 43 below and is therein conveyed to the 5 other end wherefrom it rolls laterally through the chute 43' to be elevated in its turn by the block 40 for another service.

Among the more notable advantages of the invention is the subjection of the briquets to a prolonged action thereupon of heat which facilitates the action of the binder or adhesive components of the material, so that the product delivered is in condition for use without further processes.

15 From the repetition of pressures exerted upon the briquets while under the influence of heat the components of the briquets are most intimately united to produce a fuel which is exceptionally high in calorific 20 value. The quantity of briquets manufactured from a single machine will be in accordance with the speed at which the plunger is reciprocated and should be in inverse proportion to the length of the barrel, that 25 is to say, assuming that the briquets are to be subjected to the influence of the heat for a determinate time, it is obvious that the speed at which they can be propelled through the short barrel must be less rapid than with 30 a longer barrel.

Having described my invention, what I claim is—

1. The combination with the barrel, and a plurality of dividing plates arranged to act 35 within the barrel, of a plunger arranged to successively act against the dividing plates, means for reciprocating the plunger, means operated by the plunger to elevate and position said dividing plates so that the same 40 may be forced into said barrel by said plunger, and means to furnish a charge of material between the successively acted upon dividing plates.

2. The combination with the barrel provided with an aperture for receiving the charges to be briqueted, the dividing plates, a plunger arranged to act within the barrel, and means for reciprocating the plunger, of means actuated by the plunger for successively delivering said plates into condition to be engaged by the plunger.

3. In combination with the barrel, a plunger operating therein, means to reciprocate said plunger, a plurality of dividing plates, 55 and means actuated by said plunger for automatically delivering said plates thereto.

4. A machine of the type described comprising a charge receiving barrel, a plunger and means to reciprocate the same in said 60 barrel, dividing plates, said plates being fed by said plunger into said barrel between successive charges, means to segregate the plates from the formed briquets and to lower the same, means to convey the plates to the 65 receiving end of the barrel, and means oper-

ated by the plunger to raise said plates successively in position to be fed thereby into the barrel.

5. The combination of a barrel formed of a plurality of connected sections, one of the 70 intermediate of said sections being bored to a greater diameter than the remainder, a power actuated plunger arranged to be reciprocated in said barrel, dividing plates, and means to supply said plates one by one 75 to the barrel in advance of the plunger and between each successive operative stroke of the latter.

6. The combination of a barrel formed of a plurality of connected sections, one of the 80 intermediate of said sections being bored to a greater diameter than the remainder, a tubular casing about said sections to afford spaces for a heating medium, a power actuated plunger arranged to be reciprocated in 85 said barrel, dividing plates, and means to supply said plates one by one to the barrel in advance of the plunger and between each successive operative stroke of the latter.

7. The combination with the barrel a plurality 90 of plates adapted to be propelled through the bore of said barrel, a plunger arranged to act in the barrel to effect such propulsion of the plates, means to reciprocate the plunger, a hopper communicating with the bore of the barrel, separate means operated by the plunger for delivering one of said plates to the barrel between each successive operative stroke of the plunger, and means for separating the plates from the 100 completed briquets after they are emitted from the barrel.

8. The combination with the barrel provided with a feed aperture, a plurality of plates adapted to be propelled through the 105 bore of said barrel, a plunger arranged to act in the barrel to effect such propulsion of the plates, means to reciprocate the plunger, a hopper communicating with the bore of the barrel through said aperture, separate 110 means operated by the plunger for delivering one of said plates to the barrel between each successive operative stroke of the plunger, and means for separating the plates from the completed briquets after they are 115 emitted from the barrel.

9. The combination with the barrel provided with a feed aperture, a plurality of plates adapted to be propelled through the bore of said barrel, a plunger arranged to 120 act in the barrel to effect such propulsion of the plates, means to reciprocate the plunger, a hopper communicating with said bore of the barrel through said aperture, a gate arranged to close the bore opening to one 125 side of said feed aperture when the plunger is retracted, means co-acting with the plunger for delivering one of said plates to the barrel between each succeeding operating stroke of the plunger, said means also serv- 130

ing to open the gate prior to such operative strokes, and means for separating the plates from the completed briquets after they are emitted from the barrel.

- 5 10. The combination with the barrel, a casing about the barrel to afford space for a heating medium, a plurality of plates adapted to be propelled through the bore of said barrel, a plunger arranged to act in the barrel to effect such propulsion of the plates, means to reciprocate the plunger, a hopper communicating with the bore of the barrel, a spring-pressed gate arranged to close the bore opening when the plunger is 10 retracted, means co-acting with the plunger for delivering one of said plates to the barrel between each succeeding operative stroke of the plunger, said means also serving to open the gate prior to such operative stroke, 15 means for separating the plates from the completed briquets after they are emitted from the barrel, and means for conveying said plates to the aforesaid means which deliver them to the barrel.
- 15 20. The combination with the barrel, provided with a feed aperture, a casing about the barrel to afford space for a heating medium, a plurality of plates adapted to be propelled through the bore of said barrel, a plunger arranged to act in the barrel to effect such propulsion of the plates, means to reciprocate the plunger, a hopper communicating with the bore of the barrel, through said aperture, separate means actuated by the plunger for automatically delivering one of said plates to the barrel between each succeeding operative stroke of the plunger, and means for separating the plates from the completed briquets after they 25 are emitted from the barrel embodying an inclined spout.
- 25 30. The combination with the barrel provided with a feed aperture, a plurality of plates adapted to be propelled through the bore of said barrel, a plunger arranged to act in the barrel to effect such propulsion of the plates, means to reciprocate the plunger, a hopper communicating with the bore of the barrel through said aperture, means actuated by the plunger for delivering one of the plates to the barrel between each succeeding operative stroke of the plunger, means for separating the plates from the completed briquets after they 35 are emitted from the barrel embodying an inclined spout.
- 30 35. The combination with the barrel provided with a feed aperture, a plurality of plates adapted to be propelled through the bore of said barrel, a plunger arranged to act in the barrel to effect such propulsion of the plates, means to reciprocate the plunger, a hopper communicating with the bore of the barrel through said aperture, means actuated by the plunger for delivering one of the plates to the barrel between each succeeding operative stroke of the plunger, and means for separating the plates from the completed briquets after they 40 are emitted from the barrel embodying an inclined spout.

- 40 45. The combination with the barrel provided with a feed aperture, a plurality of plates adapted to be propelled through the bore of said barrel, a plunger arranged to act in the barrel to effect such propulsion of the plates, means to reciprocate the plunger, a hopper communicating with the bore of the barrel through said aperture, means actuated by the plunger for delivering one of the plates to the barrel between each succeeding operative stroke of the plunger, and means for separating the plates from the completed briquets after they 50 are emitted from the barrel, and means for conveying said plates to the aforesaid means which deliver them to the barrel.
- 50 55. The combination with the barrel provided with a feed aperture, a casing about the barrel to afford space for a heat medium, a plurality of plates adapted to be propelled through the bore of said barrel, a plunger arranged to act in the barrel to effect such propulsion of the plates, means to reciprocate the plunger, a hopper communicating

with the bore of the barrel through said aperture, a spring-pressed gate arranged to close the bore opening to one side of said feed aperture when the plunger is retracted, means co-acting with the plunger for delivering one of said plates to the barrel between each succeeding operative stroke of the plunger, said means also serving to open the gate prior to such operative strokes, means for separating the plates from the completed briquets after they are emitted from the barrel, and means for conveying said plates to the aforesaid means which deliver them to the barrel.

70 75. 14. A briquetting machine comprising a barrel provided with an opening for the supply of the successive charges of material to be briquetted, a plunger arranged for reciprocation in one end of said barrel, means for effecting such reciprocation, a plurality of dividing plates, automatic means to positively supply one of said dividing plates to the barrel prior to each operative stroke of the plunger, means to segregate the dividing plates from the briquets, means whereby the dividing plates are conveyed from the delivery end of the barrel to the aforesaid means which supply them to the barrel, and means to positively engage the dividing plates at the point of segregation and to deliver same to said conveying means.

90 95. 15. In a briquetting machine, a barrel and a plunger therein, dividing plates for the material, means to deliver the plates to said plunger so that the same may be forced in said barrel, and a rotating element for removing the plates at the completion of the briquet and delivering the same to said first named delivery means, said element including a series of arms.

100 105. 16. In a briquetting machine, a barrel and a plunger therein, dividing plates for the material, and means to engage the plates at the completion of the briquet, lower the same, convey the same to the receiving end of the barrel, and elevate the same at said receiving end.

110 115. 17. In a briquetting machine, a barrel and a plunger therein, dividing plates for the material, rotary means at the delivery end of said barrel to engage the plates and lower the same, means to convey the plates to the receiving end of the barrel, and means to elevate the plates at said receiving end.

120 125. 18. In a briquetting machine, a barrel and a plunger therein, dividing plates for the material, means to convey said plates from the delivery end of the barrel to the receiving end, and means to lower said plates onto said conveying means embodying a multi-armed rotatable element.

130 135. 19. In a briquetting machine, a barrel and a plunger therein, dividing plates for the material, means to convey the plates from the delivery end of the barrel to the receiv-

ing end, and rotatable means actuated by the weight of the plates to deliver the plates onto said conveying means.

20. In a briquetting machine, a barrel and a plunger therein, dividing plates for the material, means to convey the plates from the delivery end of the barrel to the receiving end, a part on which the briquets and plates are moved, a chute to receive the briquets spaced from said part, and means operating in said space to deliver the plates onto said conveying means.

21. In a briquetting machine, a barrel and a plunger therein, a hopper let into said barrel, means to close the outer side of said hopper at the point where it enters said barrel, dividing plates for the material, and means for raising said plates to a position where the plunger may force the same in said barrel, said plates engaging said hopper closing means and raising the same.

22. In combination with a barrel formed to have an intermediate part of greater diameter than the remainder thereof, a plunger operating in said barrel to force the material through said barrel, the material expanding in said enlarged part of the barrel and subsequently being compressed to resume its travel through the remainder of the barrel, whereby the briquet furnishes a resisting force to retard the forward movement of the plunger.

23. In combination with a plunger, a barrel in which the plunger operates, the barrel being so formed whereby the plunger in its forward movement is retarded by the material which latter is allowed to expand and is then compressed in said barrel.

24. In combination with a barrel, and a plunger therein, dividing plates for the material, means to convey the plates from the delivery end of the barrel to the receiving end thereof, means operated by the weight of the plates to lower the same from the delivery end of the barrel onto said conveying means, and spring impelled means to engage said lowering means and restrict the movement thereof.

25. In combination with a barrel, a plunger therein, and dividing plates for the material, means to separate the finished briquets from said plates, consisting of an inclined part on which said finished briquets and said plates move, means at the upper end of said inclined part to receive the finished briquets, and means operating between said inclined part and said receiving means to remove the plates.

26. In combination with the barrel, and a plunger reciprocating therein, a plurality of dividing plates, means to automatically

and successively position said plates so that the same will be carried by said plunger into the barrel, means to actuate said plunger, and means to operate said first 65 named means.

27. In combination with the barrel and a plunger therein, means to reciprocate said plunger, a plurality of dividing plates, means to automatically deliver said plates 70 in such position so that the same will be carried by said plunger into the barrel, and means to automatically separate said plates from the completed briquets and to convey the same to said delivery means.

28. In combination with the briquet forming mechanism, a plurality of dividing plates each of greater weight than a completed briquet, and gravity means to separate the completed briquet from said plates 80 actuated by the weight of individual plates.

29. In combination with the briquet forming mechanism, a plurality of dividing plates each of greater weight than a completed briquet, and means to separate said 85 plates from the completed briquet, said means being unaffected by the weight of a completed briquet, but being actuated by the weight of a plate.

30. In combination with a barrel and a plunger therein, with means for reciprocating said plunger, a plurality of dividing plates, and means operated by said plunger during its idle stroke for automatically moving a plate in position to be engaged by 95 said plunger to be moved into said barrel on the working stroke thereof.

31. In a briquetting machine, a barrel and a plunger therein, a hopper communicating with the barrel for feeding briquet material thereto, means to control said communication between said barrel and hopper, and automatic means to open said controlling means, prior to said plunger entering the barrel and for closing the same after said 105 plunger leaves the barrel.

32. In a briquet machine employing dividing plates disposed between adjacent completed briquets, means to separate said plates from the completed briquets including an 110 inclined part up which the briquets and plates are moved so as to successively project the briquets and plates beyond the termination of said inclined part so as to leave the same unsupported and subject to 115 the action of gravity.

In testimony whereof I affix my signature in presence of two witnesses.

GEORGE WINTER HERBEIN.
